DESIGN FOR A WELDING ELECTRODE EXTRUDER COVERING MACHINE

Claude J. Holslag, South Orange, N. J., assignor
to Electric Arc, Inc., Newark, N. J.

Application September 22, 1942, Serial No. 108,315

Term of patent 14 years

To all whom it may concern:

Be it known that I, Claude J. Holslag, a citizen of the United States, residing at South Orange, in the county of Essex, State of New Jersey, have invented a new, original, and ornamental Design for a Welding Electrode Extruder Covering Machine, of which the following is a specification, reference being had to the accompanying drawings, forming a part thereof.

In the drawings:

Figure 1 is a perspective view of one side of a welding electrode extruder covering machine showing my new design; and

Figure 2 is a perspective view of the opposite side thereof.

I claim:

The ornamental design for a welding electrode extruder covering machine, as shown.

CLAUDE J. HOLSLAG.
